DENTAL DIE TRAY

Arthur J. White, 6117 Elm St.,
Raytown, Mo. 64133

Filed Sept. 13, 1967, Ser. No. 8,579

Term of patent 14 years

(Cl. D24—1)

Fig. 1.

Fig. 4.

Fig. 2.

Fig. 5.

Fig. 3.

Fig. 6.

FIG. 1 is a rear perspective view of a dental die tray embodying my new design.

FIG. 2 is a top plan view of same;

FIG. 3 is a bottom plan view of same;

FIG. 4 is a side elevational view of same, the opposite side elevation being the same;

FIG. 5 is a rear elevational view of same; and

FIG. 6 is a front elevational view of same.

I claim:

The ornamental design for a dental die tray, as shown and described.
